(57) **CLAIM**

The ornamental design of a drinking spout, as shown and described.

DESCRIPTION

FIG. 1 is a perspective view of a drinking spout showing my new design;

FIG. 2 is an enlarged front elevational view thereof, the rear elevational view being a mirror image thereof.

FIG. 3 is a side elevational view thereof, the opposite side being a mirror image thereof.

FIG. 4 is a top plan view thereof; and,

FIG. 5 is a bottom plan view thereof.

The broken line showing of a beverage can in FIG. 1 is included for the purpose of illustration and forms no part of the claimed design.
